MILO E. RICE, OF KANSAS CITY, MISSOURI

ARTIFICIAL ANKLE JOINT

Application filed February 3, 1930. Serial No. 425,534.

This invention relates to ankle joints for artificial legs, and has for its general object to produce a construction which will allow the leg to assume an angle with regard to the foot, in a plane at an angle transverse to the plane of the longitudinal center of the foot, as, for example, when the wearer of the leg places the foot on a side hill or surface extending transversely of the length of the foot.

As far as I am aware no one has yet produced an ankle joint which was commercially successful in accommodating a large angle of variation as above recited without danger of the joint becoming separated and leading to the fall of the wearer. In certain other types of construction the swinging or rocking of the leg with respect to the foot is restricted to a plane parallel to a plane passing through the longitudinal center of the foot with no accommodation to meet transverse inclination as mentioned. With this type of leg the wearer is subjected to side strain or injury to the stump when he places the foot on a side hill or similar inclined surface.

A further object of the invention is to produce an artificial ankle joint which is of strong, durable, efficient, simple and light construction having a minimum of operating parts and which will be substantially noiseless in use and will cushion the vibration, shock or jar so that it is greatly diminished before it reaches the wearer of the leg.

With the general objects named in view and others as will hereinafter appear, the invention consists in certain novel and useful features of construction and organization of parts as hereinafter described and claimed; and in order that it may be fully understood, reference is to be had to the accompanying drawing, in which:

Figure 1 is a central vertical section through an artificial ankle joint embodying the invention.

Figure 2 is a section on the line II—II of Figure 1 with part of the leg in elevation and with the resilient sleeve omitted.

Figure 3 is a section through the locking or retaining bar for the heel cord which is

used to limit the forward rocking movement of the leg on the ankle joint.

Figure 4 is a perspective view of a slightly modified form of ball joint.

In the said drawing, where like reference characters identify corresponding parts in all of the figures, 1 indicates an artificial leg which is preferably hollow as illustrated. The lower end of the leg is reduced as at 2, and said reduced portion, in a plane extending longitudinally of the foot, is bifurcated and terminates in a pair of semi-spherical shaped ends or balls 3 and 4.

The ends 3 and 4 in the preferred construction are provided with individual metallic caps or balls 5. In the modified construction shown in Figure 4, the ball joints are cast integrally as at 6 and are provided with a pair of upwardly extending straps 8 to be fastened to the reduced end 2 of the leg.

The foot 9 of the invention is provided with a pair of semi-spherical sockets 10 and 11, spaced equal distances on opposite sides of the longitudinal center line of the foot. The sockets 10 and 11 are preferably lined with leather 12 or other cushioning and sound-deadening and wear-resisting material which preferably is made of a single piece and provides an abutment wall 13 between the two sockets.

Referring to Figure 1, it will be evident that the leg can rock back and forth in a plane parallel to the length of the foot on the balls 5 in the sockets 10 and 11, the forward movement being limited by heel cord 14 secured at one end in a groove 15 formed in the rear end of heel of the foot 9 and extending upwardly through the reduced portion 2 of the leg and having its upper end secured to a cross pin 16 carried by the leg as illustrated. The foot and leg are fitted in a resilient sleeve joint 17 which deadens the sound and cushions the jar incident to walking and binds the parts together.

When the wearer of a leg equipped with an ankle joint as described, steps on a surface inclined transversely of the length of the foot (see Figure 2), it is possible for the parts to rock on one of the ball and

- socket joints as illustrated, and if the angle is extreme, the other ball may move completely out of its respective socket. It will be evident that with the construction described and illustrated there is not the remotest possibility that the joint will slip out of the socket and permit the wearer to fall as the supporting area of the ball and socket is always practically constant regardless of the angle formed between the foot and the leg. The foot cannot become detached from the ankle nor the balls disengaged from their sockets, as the foot is bound to the leg by a resilient rubber or other suitable covering 10 as common in the art. After the foot has rocked as described, the resiliency of the cover and the gravitational weight of the foot will always cause it to return to normal position.
- 15 20 From the above description, it will be apparent that I have produced a construction which embodies all of the features of advantage set forth as desirable, and while I have described and claimed the preferred embodiment of the same, it is to be understood that I reserve the right to make all changes permissible over the prior art.

I claim:

1. In an artificial leg structure, a foot portion having an ankle-joint plate consisting of two integral laterally-aligned sockets occupying planes at opposite sides of the longitudinal center of the foot portion, and a pair of arms rigid with and projecting upward from the sockets at the outer sides and midway the length thereof.
2. In an artificial leg structure, a leg portion having a depending shank provided with laterally-spaced depending semi-spherical portions, a foot portion having a pair of laterally-spaced semi-spherical sockets receiving said pair of semi-spherical portions to constitute independent fulcrums upon either of which the foot portion can tilt laterally relative to the leg portion, to permit the other semi-spherical portion and socket to separate, and an elastic shoe completely encasing and tightly fitting the foot and shank portions and bearing at its upper edge firmly against the lower end of the leg portion around the shank.

In testimony whereof I affix my signature:

MILO E. RICE.
